UNITED STATES PATENT OFFICE.

WILLIAM ADAM SIEGNER, OF STRATFORD, AND WILLIAM DOUGLAS GRAHAM, OF BRANTFORD, ONTARIO, CANADA.

ROADWAY CROSSING INTERSECTING RAILROAD TRACK.

Application filed February 28, 1925. Serial No. 12,444.

To all whom it may concern:

Be it known that we, WILLIAM ADAM SIEGNER and WILLIAM DOUGLAS GRAHAM, both subjects of the King of Great Britain, 5 and residents, respectively, of the city of Stratford, in the county of Perth, in the Province of Ontario, Canada, and the city of Brantford, in the county of Brant, in the Province of Ontario, Canada, have invented 10 certain new and useful Improvements in Roadway Crossings Intersecting Railroad Tracks, of which the following is the specification.

Our invention relates to improvements in 15 roadway crossings intersecting railroad tracks, and the object of the invention is to devise a simple, cheap, durable construction which may be readily installed in position, which will not be affected by change in climatic conditions, and any parts of which 20 may be easily replaced whenever desired, and it consists essentially of the arrangement and construction of parts hereinafter more particularly explained.

Fig. 1 is a plan view of a railway track 25 showing our roadway crossing applied thereto.

Fig. 2 is an enlarged sectional view on line 2—2, Fig. 1.

Fig. 3 is a cross sectional view on line 3—3, Fig. 1.

Fig. 4 is a sectional detail on line 4—4 Figure 1.

Fig. 5 is a sectional detail on line 5—5 Figure 2.

In the drawings like characters of reference indicate corresponding parts in each figure.

1 and 2 indicate the rails of a railway track, and 3 the ties upon which the rails are secured in the usual manner. The ties 3 are spaced apart in the usual way and embedded in ballast 4, according to common practice. The rails 1 and 2 are supported 45 upon chairs 1^x and 2^x in the usual manner. 5 are inverted T bars which are secured to ties 3 and extend longitudinally thereof between and to the outside of each rail. 7 are mud rails which are usually located at the 50 inside of each track rail. 8 are a series of scrap rails which are inserted and located between the rails 1 and 2 and parallel therewith, and spaced apart as indicated. The base flanges of the rails 8 are provided with 55 cut-out portions X for passage of tongues 11.

The base flanges 8 lie horizontally in the same plane.

The rails 8 are held in position by T bars 5 which have cut-out portions into which the inverted heads of the rails 8 fit the T 60 bars being secured to the ties and serving as chair supports for the rails 8.

9 and 9^x are tread plates which are supported upon the base flanges of the inverted rails 8.

The edges of the outer plates 9^x extend parallelly to the rails 1 and 2 and are down-turned over the upper edge of the base flange 7° of each rail 7. The centre plate 9 is provided with a series of bayonet slots 10 70 through which securing bolts 10^x extend having washers 10° which are preferably rectangular and which grip the edges of the base flanges 8^x to hold the centre plate in position. 11 are tongues which are stamped 75 down out of the metal of the tread plates 9^x. The tongues 11 engage the edges of the base flanges of the rails 8 by moving the plates 9^x in a direction parallel with the rails, the plates sliding on the upwardly directed 80 faces of the base flanges to the desired position.

In narrow crossings the plates 9 are dispensed with and in order to secure the plates 9^x in position all that it is necessary to do is 85 to lay a plate 9^x horizontally upon the upwardly directed faces of the base flanges of the rails 8 at the ends of the rails at one side of the crossing and slide such plate longitudinally of the rails towards the centre 90 thereof so that the tongues 11 are in a position to pass beneath the base flanges of the rails 8 into the position shown in Fig. 6. The other plates 9^x are then similarly placed in position from the opposite ends of the 95 rails 8. In wide crossings where a number of plates 9^x extend both between and at the outside of the rails 1 and 2, we provide cut out portions X in the base flanges of the rails 8 through which the tongues 11 pass as 100 the plate 9^x is laid on the base flanges of the rails 8. The plates 9^x are then slid successively to their final position at one side of the crossing at the ends of the rails 8, the tongues 11 assuming the position shown in 105 Fig. 6. The centre plates 9 are then bolted in position by means of the bolts 10^x passing through the slots 10, the bolts drawing the washers 10° into engagement with the lower face of the base flanges of the rails 8. The 110

plates 9* at the other side of the crossing are then placed in position in a similar manner to the aforementioned plates 9*.

When it is necessary to insert new ties beneath the plate 9*, the centre plate 9 is removed and one or the other of the plates 9* slid horizontally towards the cut out portion X of rail 8 when it can be removed by lifting, or slid off at end of supporting rails 8.

13 are inclined plates which are provided with tongues 13* engaging the outer edges of the plates 9*, the lower edges of the plates 13 extending down into the ballast or to the top of adjoining tie 4, as indicated in Fig. 3, adjacent to one of the ties 3.

By this means the entrance of snow is prevented beneath the cross plates 9, and the plates are prevented from being lifted or dragged by obstacles dragging from cars. The end edges of the plates 13 are notched as indicated at 13* so as to fit closely to each track rail 1 and 2.

When the rails are bonded together, as is the case in electric railways, the mud rails 7 are insulated from the track rails 1 and 2 by a layer of insulating material 22.

It will be seen from this description that we have provided a very simple construction of roadway crossing which may be readily installed, which will freely expand or contract under climatic changes, which will be durable, and which may be readily repaired whenever desired.

In certain cases it may be desirable to dispense with the plates 9 and 9*, the base flanges 8* of the rails 8 being placed in edge contact forming in themselves a continuous tread surface.

What we claim as our invention is:

1. The combination with the track rails and supporting ties, of a series of members arranged between and parallel with the track rails, and having horizontally flanged upper ends forming tread bearing means, inverted T bars secured to the ties and extending transversely of the aforesaid members, and having cut-out portions through which the members extend.

2. The combination with track rails and supporting ties, of a series of spaced apart

members carried by the ties parallel with the rails, plates supported upon such members between and on the outside of each track rail, and detachable means for connecting the plates to the members.

3. The combination with track rails and supporting ties, of a series of spaced apart members having laterally flanged upper ends and carried by the ties parallel with the rails, plates supported upon the flanges of such members between and on the outside of each track rail, and engaging means carried by the plates and adapted to be slid into and out of engagement with the flange edges of the aforesaid members.

4. The combination with track rails and supporting ties, of a series of spaced apart inverted headed members carried by the ties parallel with the rails, plates supported upon such members between and on the outside of each track rail, having transverse slots located at each side of such members, and bolts extending through the slots of the plates to engage the aforesaid members for adjustably securing the plates in position.

5. The combination with track rails and supporting ties, of a series of supporting members extending parallelly with the track rails and spaced apart, tread plates detachably secured thereto, an inclined plate secured to the outer end edges of the tread plates extending at their ends adjacent to the track rail and extending at their lower edges into the track ballast.

6. The combination with track rails and supporting ties and mud rails having their base flanges set vertically and carried by the ties at the inside of each track rail, of a series of tread plate supporting members carried by the ties parallel with the track rails and spaced apart, tread plates supported upon the supporting members, detachable connecting means between the tread plates and supporting members, and downturned flanges extending from the lateral edges of the tread plates located between the track rails and over the upturned edge of the mud rail base flange.

WILLIAM ADAM SIEGNER.
WILLIAM DOUGLAS GRAHAM.
